U.S. Cl. D15—8

Fig. 1

The end of the prayer rail not shown is a mirror image of the end shown while the back of the article is conventionally plain.

I claim:

The ornamental design for a prayer rail, as shown and described.
